UNITED STATES PATENT OFFICE

RICHARD PASTERNACK, OF BROOKLYN, NEW YORK, ASSIGNOR TO CHARLES PFIZER & COMPANY, OF BROOKLYN, NEW YORK, A CORPORATION OF NEW JERSEY

DENTIFRICE

No Drawing.

Application filed December 20, 1929. Serial No. 415,611.

This invention relates to improvements in dentifrices and more particularly to the base used in such dentifrices.

An object of this invention is to provide 5 a dentifrice having a base possessing the advantageous properties of the bases heretofore known and, furthermore, being more palatable than the heretofore known bases.

A further object is to provide a dentifrice 10 having a base which is peculiarly adapted not to irritate the gums.

A still further object is to provide a tooth 15 paste in which the solid and liquid ingredients will remain in a homogeneous mixture after being filled into tubes.

An acceptable base must assist in the mechanical cleansing action of the tooth brush without causing undesirable abrasion of the teeth, and must be compatible with various 20 chemicals used in dentifrices for maintaining the teeth and gums in a healthy condition, such as weak acids, mild astringents, deodorants and disinfectants.

Substances such as calcium carbonate and 25 phosphate, magnesium carbonate and hydroxide, are not entirely satisfactory, as they leave disagreeable "chalky" after-taste in the mouth and because of relative insolubility tend to irritate the gums and leave fine 30 particles lodged in the gums.

Another objection to bases heretofore known is that the solid and liquid ingredients of tooth pastes employing these bases have a tendency to separate on storing, this tendency being particularly noticeable with considerable changes in temperature.

The present invention lies in the discovery 40 that salts of gluconic acid are well suited for use as the base for dentifrices, having properties materially more favorable for such use than the substances heretofore used. Of these salts of gluconic acid, the calcium and magnesium gluconates are preferred.

These gluconates are distinguished from 45 bases heretofore known in that they leave no "chalky" after-taste, and due to their relatively great solubility in water, calcium gluconate being about 3% and magnesium gluconate being about 16% at body temperature, 50 particles of the same can be completely re-

moved from the mouth by rinsing with water, thereby eliminating any tendency to irritate the gums. Because of the high solubility of magnesium gluconate, a dentifrice containing the same is of great value to persons with tender gums. For such gums, a polishing agent whose particles dissolve very quickly is desirable. Furthermore, these salts have a mild cleansing action without undesirable abrasion of the teeth, and are not affected by the various chemicals used in dentifrices.

These gluconates are further distinguished from bases heretofore known in that they form with the liquid ingredients of a tooth 65 paste, a homogeneous mixture which shows no tendency to separate into its component parts. This is true even where the commonly used binders such as gums are omitted from the mixture. This desirable property 70 of these gluconates is due to their peculiar crystalline structure which is such that liquids are readily absorbed and the mixture becomes "plastic" similar to mixtures of clay and liquids.

To illustrate the invention, the following examples of dentifrices are given, parts by weight, but it is to be understood that the invention is not restricted to these examples:

Example I. The following is a composition of a tooth paste embodying the invention:

Calcium gluconate	100 parts
Gluconic acid	4 parts
Glycerin	50 parts
Water	40 parts
Flavoring	to suit

Example II. A tooth powder composition embodying this invention is as follows:

Calcium gluconate	100 parts
Magnesium peroxide	2 parts
Flavoring	to suit

Example III. A second tooth powder composition embodying this invention is as follows:

Calcium gluconate	100 parts
Zinc citrate	1 part
Flavoring	to suit

Magnesium gluconate can be substituted for the calcium gluconate in the above examples without otherwise changing the composition.

- 5 The invention claimed is:
1. A dentifrice comprising a cleansing and polishing agent consisting of a member selected from the group consisting of calcium gluconate and magnesium gluconate.
  - 10 2. A dentifrice comprising a cleansing and polishing agent consisting of calcium gluconate.
  - 15 3. A dentifrice comprising a cleansing and polishing agent consisting of magnesium gluconate.
  - 15 4. A dentifrice comprising from 50 to 98% calcium gluconate.

Signed at Brooklyn, in the county of Kings, and State of New York, this 17th day of

20 December, A. D. 1929.

RICHARD PASTERNACK.
